[57] CLAIM

The ornamental design for an electronic calculating
machine, as shown and described.

DESCRIPTION

FIG. 1 is a perspective view of an electronic calculating
machine showing our new design;
FIG. 2 is a top plan view of the machine in collapsed
position;

FIG. 3 is a front elevational view thereof;

FIG. 4 is a rear elevational view thereof;

FIG. 5 is a right-hand side elevational view thereof; and
FIG. 6 is a bottom plan view thereof.
